United States Patent Office

Des. 202,670
Patented Oct. 26, 1965

202,670

ADDING MACHINE

Helmut Riffert, Zetel, and Alfons Boothby, Wilhelms-haven, Germany, assignors to Olympia Werke A.G., Wilhelmshaven, Germany

Filed July 20, 1964, Ser. No. 80,937

Claims priority, application Germany Apr. 27, 1964

Term of patent 14 years

(Cl. D64—11)

FIG. 1

FIG. 2

FIG. 3

FIG. 4

FIG. 1 is a perspective side view of the adding machine showing our new design;

FIG. 2 is a perspective top view of the same;

FIG. 3 is a perspective front view of the adding machine; and

FIG. 4 is a perspective rear view.

The dominant features of our design reside in those portions shown in full lines on the drawings.

We claim:

The ornamental design for an adding machine, as shown, and described.
